STONE CATCHER

Herman E. Zitkowski, Denver, Colo.

Application February 18, 1946, Serial No. 648,254

4 Claims. (Cl. 209—456)

1

This invention relates to apparatus for removing relatively heavy material from articles adapted to be moved along a passage by liquid, and more particularly to a stone catcher, preferably of the jiggling type, adapted to remove sand and stones from sugar beets being carried by water along a flume to a mill.

It is particularly necessary to effectively remove stones and sand from sugar beets, preparatory to extraction of the sugar content therefrom, to prevent damage to mill machinery, such as slicing knives. In a previous type of stone catcher, the beets are carried by water flowing through the stone catcher, and are maintained at or near the top of the body of water by a jiggling motion imparted to the water. Sand and stones settle to the bottom of the catcher, to be periodically removed by hand, as by rakes, shovels, or the like. However, such removal of collected sand and stones reduces the normal capacity of the apparatus, as it interferes with the normal flow of beets therethrough. Also, a mixture of sand and stones is difficult to handle effectively, the larger stones tending to interfere with the effective removal of sand, and vice versa. As will be evident, the removal of collected sand and stones should not interfere with the normal progress of the beets, nor should it require an undue amount of the time of an operator. Also, the stone catcher should be sufficiently reliable in operation that constant attention by an operator is unnecessary, and therefore desirably should operate automatically or semi-automatically.

Among the objects of this invention are to provide an improved stone catcher, or apparatus for removing relatively heavy material from articles adapted to be moved along a flume or similar passage by liquid, such as water; to provide such apparatus in which a jiggling motion is imparted to the water contained therein, and sand and stones are collected effectively; to provide such apparatus in which the collected sand and stones are removed periodically, either automatically or with little effort on the part of the operator; to provide such apparatus in which collected stones are removed without the necessity of the operator plunging rakes or similar tools into the body of water in the apparatus; to provide such apparatus in which the removal of collected sand is accomplished automatically and in synchronization with the jiggling motion imparted to the water; to provide such apparatus which segregates the sand and smaller stones from the larger stones; to provide such apparatus in which sand and smaller stones are removed

2

automatically and periodically at different portions of the apparatus; and to provide such apparatus which will be efficient and reliable in operation. Other objects and the novel features of this invention will become apparent from the description which follows.

Apparatus constructed in accordance with this invention may comprise a passage section having lateral partitions in the lower portion thereof forming compartments, and valves which are opened and closed automatically at periodic intervals for removing settled material. Such apparatus may also include outwardly sloping grate bars, and a valve in the wall of the apparatus just above the grate bars, for removing larger stones settling onto the grate bars. The jiggling motion may be imparted to the water by a plurality of plungers, and the automatic valves are preferably opened and closed in synchronization with the movement of the plungers, preferably by the drive means for the plungers. Additional features and the details of a preferred embodiment of this invention are illustrated in the accompanying drawings, in which:

Fig. 1 is a vertical longitudinal section of apparatus constructed in accordance with this invention;

Fig. 2 is a top plan view of the apparatus of Fig. 1; and

Fig. 3 is a lateral vertical section taken along line 3—3 of Fig. 2.

The apparatus illustrated in the drawings includes a tank T having side walls 9, as in Fig. 3, and provided with a jiggling section J, as in Fig. 2. Jiggling section J is disposed centrally and extends longitudinally of the tank, and the side walls 10 thereof divide the tank into two passages P, each extending between walls 9 and 10, as in Fig. 3. Water and beets enter tank T from a flume or the like, through diverging entrance sections 11 of Fig. 2, and are discharged to another flume or the like, as through converging discharge sections 12. Jiggling section J includes a plurality of cylinders 13, as in Figs. 1 and 3, in which pistons or plungers 14 are reciprocated, each plunger moving on the down stroke at a different time from the other plungers, as is evident from the arrows of Fig. 1. The impulses or jiggling motion thereby imparted to the body of water contained within the tank T maintains the water in a constant state of agitation, and thereby maintains the beets in the upper portion of the water within the tank. The water level in the tank T is well above the tops of partitions 15, which divide the tank into sections corresponding

to the jiggling cylinders 14, so that the thrust imparted to the water during the down stroke of each plunger will be more effectively transferred to the upper portion of the body of water.

The beets and water move through the passages P, at a slower rate than in the flume, so that heavier material, such as sand and stones, separates out and falls downwardly through the water. The beets, of course, are maintained in the upper portion of the body of water by the agitation thereof. Sand and smaller stones collect on the bottom 16 of tank T, while larger stones collect on a plurality of outwardly and downwardly sloping grate bars 17, which extend transversely from each side wall 10 of jiggling section J to the lower corners of the tank, as in Fig. 3. Sand collecting in the bottom of each compartment formed between partitions 15 is removed periodically through ports 18 in the bottom 16 of the tank, by means of valves 19, which are preferably opened in synchronization with the movement of the plunger directly above. As in Fig. 1, each valve 19 is opened as the plunger 13 directly above is on the up stroke, and closed at the beginning of the down stroke, so that the loss of water will be minimized and also so that a flow of sand and water from as great an area as possible around the port will take place.

A stem 20 of each valve 19 extends downwardly through the corresponding valve port and also through a guide 21. The valves 18 are opened by cams 22, mounted on a shaft 23 which extends longitudinally beneath the bottom of the tank and which is journaled in bearings 24. The cams 22 are spaced angularly about shaft 23 in positions corresponding to the desired opening of the respective valves, and consequently in positions corresponding to plungers 14. Each valve stem is surrounded by a coil spring 25, the upper end of which engages the guide 21 and the lower end of which engages a flange 26 on the stem, the coil springs 25 insuring that each valve 19 will close at the proper time and also maintaining each flange 26, which acts also as a cam follower, in contact with the respective cam 22.

Each plunger 14, as in Figs. 1 and 3, is actuated by a crank bearing disc 27 mounted eccentrically on a plunger drive shaft 28, in turn journaled in bearings 29 mounted at the top of jiggling section J, as in Fig. 1. Each plunger 14 is attached to the lower end of a connecting rod 30, the upper end of which is provided with a sleeve bearing 31 in which disc 27 rotates, to produce an upward and downward reciprocatory movement of plungers 14. Drive shaft 28 is driven from a motor 32, through a speed reduction unit 33 driving a small gear 34, in turn meshing with a larger gear 35 mounted on shaft 28. Motor 32 and reduction unit 33 are conveniently mounted on a framework 36 atop jiggling section J, as shown.

In accordance with this invention, valve shaft 23 is driven in synchronization with plunger drive shaft 28, as by a chain 38 of Fig. 1 which engages an upper sprocket 39 mounted on plunger shaft 28 and a lower sprocket 40 mounted on valve shaft 23. If desired, sprockets 39 and 40 may be the same size, so that valve shaft 23 will be rotated at the same speed as plunger shaft 28. However, as in Figs. 1 and 2, upper sprocket 39 may be only one-half the diameter of lower sprocket 40, so that the valves 19 will open only on alternate up strokes of the corres-

ponding plunger. It will be understood that, if desired, the speed of plunger shaft 28 may bear any other whole number ratio to the speed of valve shaft 23.

Stones collecting on grate bars 17 are removed periodically, when necessary, by the operator opening gate valves provided by gates 41 of Figs. 2 and 3, one gate valve being provided at each side of each compartment of the tank. The stones pass out through openings 42, which are preferably below the upper edge of partitions 15, so that there will be little or no opportunity for beets to flow through the gate openings. Each gate 41 is adapted to slide upwardly and downwardly in guides 43, being moved by a hand wheel 44 connected to the respective gate by a rod 45 and also conveniently mounted, as on top a side wall 9 of tank T. Preferably, co-operating wedges 46, as in Fig. 3, are provided on guides 43 and adjacent the lateral edges of gates 41, to insure that the gates will close tightly when lowered.

From the foregoing, it will be apparent that apparatus constructed in accordance with this invention fulfills to a marked degree the objects and requirements hereinbefore set forth. The inclined grate bars, disposed above the bottom of the tank for separately collecting larger stones, result in more efficient operation, particularly

when in combination with the side gates and automatically operated discharge valves for the sand and smaller stones. It is relatively easy for the operator to ascertain when a sufficient number of larger stones is collected in any one compartment, and then to open manually the corresponding gate valve for discharge of such larger stones. Also, the automatic discharge of sand and smaller stones relieves the operator of the more difficult task of determining when a sufficient amount of such materials has collected. The separation of the lower portion of the tank into compartments insures that the jiggling action imparted to the body of water, by the respective plungers, will effectively separate the beets from heavier material and will maintain the beets in the upper portion of the body of water. The opening of a sand discharge valve on an up stroke of the corresponding plunger prevents too great an outflow of water through the valve, but at the same time permits sufficient water to flow through the valve to carry with it the collected sand. The synchronization of the sand discharge valve opening movements with the plungers also contributes to the effective and trouble-free operation of the apparatus. Also, the preferred opening of the valves on alternate up strokes, or multiples thereof, insures adequate discharge of collected sand, coupled with a minimum loss of water.

It will be understood, of course, that the principles of this invention may be utilized in apparatus for separating relatively heavy material from articles other than sugar beets, and that one or more novel features of this invention may be utilized without the remaining features. It will also be understood that other embodiments of this invention may exist, and that further and additional changes may be made, all without departing from the spirit and scope of this invention.

What is claimed is:

1. Apparatus for removing relatively heavy material from articles adapted to be moved along a flume by liquid, comprising a tank connected at each end to a flume; centrally disposed walls

spaced from the bottom of said tank and providing a pair of passages extending longitudinally of said tank between said central walls and the outer walls of said tank, said passages extending from flume to flume; compartment forming, lateral partitions in the lower portion of each passage; a cooperating cylinder and plunger mounted between said central walls for imparting a jiggling motion to the liquid in each compartment; drive means, including a shaft mounted above said central walls, for reciprocating said plungers upwardly and downwardly at different times; a valve adapted to cooperate with a discharge opening in the bottom of said tank beneath each plunger, for removing settled material from said compartments; a set of outwardly inclined grate bars extending laterally from said central walls to said side walls at each side, in the lower portion of each compartment; a valve cooperating with an outlet opening in the side wall of said tank just above the lower ends of each set of grate bars; and means including a shaft disposed beneath said tank and actuated from said drive means having means for opening each said bottom valve only on an upward stroke of the corresponding plunger thereabove.

2. In apparatus for removing relatively heavy material from articles adapted to be moved along a flume by liquid, including a reciprocating plunger moved upwardly and downwardly to impart a jiggling motion to said liquid, means providing spaced openings in the manner of grate bars for limiting downward movement of articles and material of a predetermined size, means for collecting relatively heavier but smaller material passing through said spaced openings, and valve means generally below said plunger for removal of such collected smaller material, the improvement which comprises means for opening and closing said valve means in synchronization with the movement of said plunger, said valve means being opened only during an upward stroke of said plunger.

3. In apparatus for removing relatively heavy material from articles adapted to be moved along a flume by liquid, as defined in claim 2, including a plurality of plungers, and collecting means and

valve means for each said plunger, wherein each said valve means is opened on alternate upward strokes of the corresponding plunger.

4. Apparatus for removing relatively heavy material from articles adapted to be moved along a flume by a liquid comprising a flow channel section divided by transverse partitions in the lower liquid flow levels thereof into a plurality of compartments, sections adjacent said compartments adapted to hold liquid to substantially the same depth as the flow level in said channel, means providing spaced openings disposed in said channel in a position intermediate the bottom of said channel and the top liquid flow level, plungers in said adjacent sections, drive means for imparting reciprocal motion to said plungers thereby causing a jiggling motion of said liquid, discharge openings in the bottom of said channel at positions adjacent said plungers, poppet-type valves having the valve heads thereof disposed in said channel for controlling the flow through said opening, valve operating means for automatically operating said valves, and means interconnecting said valve operating means and said plunger drive means in such manner that said valves are open when said plungers are being moved upwardly by the plunger drive means, said valve heads when in the opened position being effective as flow dividers to separate solid particles from the liquid flowing toward said plungers thereby facilitating the removal of said solid particles through said openings.
